UNITED STATES PATENT OFFICE.

MONTFORD MORRISON, OF CHICAGO, ILLINOIS.

METHOD OF AND APPARATUS FOR COOLING ELECTRON-DISCHARGE TUBES.

Application filed January 7, 1924. Serial No. 684,803.

The present invention relates to systems for cooling the anodes of vacuum tubes of the thermionic type, such as hot cathode X-ray tubes, hot cathode rectifiers and the like.

Among the objects of my invention are; first, to provide a more effective means for cooling anodes than used in the prior art; second, to provide a means for cooling anodes which is less dangerous to human life than those heretofore used; third, to provide a means for cooling anodes which automatically dissipates the heat of the anode from the operating room; fourth, to provide a means for cooling anodes which is more compact and practical to operate than those of the prior art; fifth, to provide a means for cooling anodes which permits the anodes to be at any electrical potential whatever independent of the electrical potential of the primary cooling device.

Fig. 1 represents a cross section of one embodiment of my improved cooling system, and Fig. 2 shows the cooling apparatus connected to an X-ray system, utilizing a rectifier preferably such as disclosed in my Patent 1,466,541, issued August 28, 1923, and a tube holder and protective device preferably such as disclosed in my application 633,712, filed April 21, 1923.

In the prior art the most effective means of cooling anodes has been probably that of operating the anodes at ground potential and supplying them with circulating water from the city's mains at ground potential. This system allows an abundance of cooling medium at a low price and low temperature, to be constantly circulated by the reverse face of the anode and is a very convenient set-up for scientific laboratories and the like where comparatively low potentials are used.

As the potentials of X-ray tubes have been gradually raised, the impracticability of this scheme at once made itself apparent, as it involves the construction of very special high voltage generators and very special tube-holders which are expensive and impracticable to operate.

To overcome this, cooling water at ground potential was at once abandoned as a hopeless means and the cooling system was insulated and suspended in open air, so that the anode of the X-ray tube might be operated at half potential above ground, which is universal practice and most economical and which allows most economical and satisfactory apparatus. Many set-ups have been

proposed to provide means for cooling this insulated system. Large glass jars have been provided and the water circulated to and from the anode by means of an insulated pump. Fans have been used to blow air against these jars and various other schemes employed, all of which proved to be entirely ineffective.

In order to make this blowing of air more effective, instead of using glass jars automobile radiators have been employed and the water circulated to and from the radiator identical with the system used in automobiles, and a fan for causing a blast of air to pass through the radiator exactly identical with the systems used in automobiles. There are many disadvantages to such a system. First of all, it is large and cumbersome, it fills up considerable space in the operating room; the radiator and connections are all at high potential above ground, making them very dangerous to the operator's life. The sharp points in the corners of the radiator give off violent corona streamers which generate obnoxious gases, sickening those about it, and the ozone generated by the corona streamers react upon the radiator parts causing them to leak, which is not only bothersome but is very dangerous to human life to have water at 150,000 volts dripping the ground. Furthermore, this system does not supply an adequately effective means for cooling, for the radiator can only reduce the temperature of the water a certain percentage and the temperature of the outgoing water grows higher and higher as the incoming water increases the temperature. Furthermore, the air being only circulated about the room the temperature of the room is raised considerably, which also raises the temperature of the cooling water being supplied to the anode. All these go to limit the effectiveness of this system of cooling to a very disadvantageous state of affairs.

In my improved system of cooling I provide an insulated circulating system but one which is enclosed within corona-proof shielding and which is only exposed to the surroundings at one place where it is necessary to make connections to my system proper, and I thereby reduce the danger to human life and further eliminate the generation of ozone and the accompanying obnoxious gases and their resultant effects.

In this system I provide substantially three circulating systems; one at the voltage

of the anode, which circulates to and from the said anode, and a second circulating system at ground potential circulating to and from a cooling means at this potential, and a third circulating system which is composed of a liquid dielectric circulating between the two aforesaid systems.

In this way my system is composed of a structure which somewhat resembles a chain 10 with the links standing out in air; the first link being the circulating system of the anode, and the second link being the dielectric circulating system between the high potential and low potential systems, and the third link being the low potential circulating system.

It will be appreciated that I may so insulate these links and operate them so that the potential between the anode and the ground 20 may be divided into any number of links instead of three, depending upon the potential and engineering economy and the particular insulation involved.

As to the means which I employ at low potential for cooling, depends upon what is available and the degree of effectiveness required by the anode. Preferably I use ordinary hydrant water from the city mains, but in some applications where still more effective means is required, I supply instead of the city mains a small refrigerating machine such as supplied for individual household use, and which is a small, compact and a most effective means for limiting the temperature 30 of the anode.

Having described my invention in general terms, reference may now be had to the accompanying drawings.

Fig. 1, 1 is a duct which conducts the cooling water away from the anode of the electron discharge tube to be hereinafter described. This heated water is conducted into a breathing chamber 2 and thence through a duct 3, to a toroidal spiral 4, formed of this 40 same duct material and located in the lower part of the tank 5, said spiral 4 is surrounded by a hollow, concentric, cylindrical barrier 6. From the toroidal spiral 4, cooling water is led up by means of a continuation of the 45 same duct 7, to a small gear pump 8, such as is used on screw-machines and the like for supplying the cooling fluid to work in process, thence by duct 9 and 10 to the anode 50 of the electron discharge tube. The gear pump 8, is driven by a motor 11, by means of an insulator-coupling 12. This allows the pump 8 to be operated at anode potential and the motor 11 to be operated at ground 55 potential.

60 In the upper part of tank 5 is located a series of helically formed concentric ducts 13 and 14 constituting a continuous duct, having an inlet at 15 and an outlet at 16. The inlet 15 may be directly connected to a city water main and the outlet 16 connect-

ed to a waste-pipe, or they may be connected to a small refrigerating plant, such as heretofore referred to, or such other cooling means as is available and at low potential.

The tank 5 is partially filled with oil or 70 other fluid insulating dielectric 17.

In the functioning of the device as a means for cooling anodes of electron discharge tubes, the operation is as follows:

Water from the city mains is connected to 75 duct 15, duct 16 is connected to a waste pipe. Water is turned on and is caused to circulate through the helical duct systems 13 and 14 thus acting to remove from the oil about these helical duct systems any excess temperature over that of the water itself.

80 Motor 11 is started and the pump 8 being primed by the hydrostatic pressure of the system, as will be appreciated by those familiar with the art, the water in the high 85 voltage duct system begins to circulate.

A pressure is developed in duct 9, forcing the water through duct 10 to the anode and back through duct 1 into the breathing chamber 2, through the duct 3 and through the 90 toroidal spiral duct circuit 4, and thence to the pump again. The water circulating through the toroidal spiral 4 imparts some of its heat to the surrounding oil, and the directing barrier 6 constrains this heated oil 95 to rise to the surface in the direction of the indicated arrows, 18 and 19.

The removal of this heated oil from about 100 toroidal spiral 4 causes its priorly occupied space to be replaced by other oil which is drawn downward from the upper helical system in the general direction of the curved arrows 20 and 21. This motion in turn 105 draws the aforementioned heated oil which has arisen to the upper region 22 and 23, through the cooling ducts 13 and 14 in the general direction of the curved arrows 24 and 25. Thus the oil in its circulation forms the middle link of the chain heretofore referred to; the high potential circulating 110 water system being one outside link and the low potential circulating system being the other outside link.

115 It will be appreciated that my invention is not limited to oil in the tank 5, nor is it limited to water circulating through 1 and 10, through 15 and 16. As a matter of fact, any suitable fluids may be used.

120 It will be appreciated that the liquid circulating through 15 and 16 may be brought to a very low temperature, depending upon the liquid used, and thus the liquid dielectric in the tank 5 may be cooled to almost any extent desired, and therefore the liquid in the high voltage circulating system may work much more effectively than those systems heretofore in use.

125 Referring to Fig. 2, the several parts of Fig. 1 will be recognized by their like numerals.

Further, the duct 1 is continued up to the anode 26 of an X-ray tube 27 and back again, forming a continuous circulating system at high potential. 38 represents a source 5 of cooling medium.

The duct line represented by 1 and 10, in Fig. 2, and more in detail in certain parts in Fig. 1, is insulated from the duct line represented by 15 and 16, Figs. 1 and 2, and 10 since the duct line represented by 15 and 16 is operated substantially at ground potential, the duct line represented by 1 and 10 is, therefore, insulated from ground and operated at potentials above that ground such 15 that the liquid flowing to and from the anode is insulated from ground, under operation.

28 is a source of alternating potential which supplies the step-up transformer 29 with energy, the circuit of which may be 20 supplied with a switch 30 for practical purposes. 31 is a high potential rectifier as described in my aforecited patent, 32 is an X-ray tube filament-heating transformer common to the art, which may be supplied 25 with a regulator 33 and a switch 34 for practical purposes. Motor 11 is supplied by

means of leads 35 and a connecting switch 36, with power from source 28. 37 is an X-ray tube holder and protective shield, as fully described in my heretofore cited patent application.

What I claim is:

In an electron discharge apparatus comprising an anode subject to elevation of temperature by electron discharge thereupon 35 and said anode subject to operation at potentials substantially above that of earth, means for circulating a liquid to and from said anode in a hollow insulated duct, means for circulating a second liquid of a lower 40 temperature than that of the aforesaid and at an electrical potential substantially that of earth and in a second hollow duct, the two said ducts immersed in a liquid dielectric providing insulation between said ducts, 45 whereby the heat of the anode is first transferred to the liquid dielectric and thence carried away by the aforesaid second liquid and duct.

In witness whereof, I have hereunto set 50 my hand this 4th day of January, 1924.

MONTFORD MORRISON.
